UNITED STATES PATENT OFFICE.

AZEL C. HOUGH, OF JANEVILLE, WISCONSIN.

SHADE APPLIANCE.

1,414,021.

Specification of Letters Patent. Patented Apr. 25, 1922.

Application filed January 29, 1921. Serial No. 440,838.

To all whom it may concern:

Be it known that I, AZEL C. HOUGH, of Janesville, in the county of Rock and State of Wisconsin, a citizen of the United States 5 of America, have invented a new and useful Shade Appliance, of which the following is a specification.

My invention relates to improvements in devices for use in connection with shades, 10 and more especially those of the wood-slat porch-shade type, when the same are located inside of window sashes in buildings, which sashes have swinging ventilating sections or ventilators, and resides in anti-friction 15 means attached to or carried by such ventilators in contacting relation to such shades, as hereinafter more fully set forth.

Said anti-friction means is of the nature 20 of a buffer, carried by the ventilator and adapted to be contacted by or to contact with a shade suspended at the top in any suitable manner, as by being attached to the ceiling of the room, or to brackets extending into the room from points below said ceiling, or 25 directly to the sash itself in connection with which said shade is employed. The buffer is a horizontal member that is rigidly secured to the ventilator in the aforesaid sash at or near the top of said ventilator on the 30 inside thereof, and may extend either the width of said ventilator or substantially the entire width of said sash, preferably the latter. The buffer must not, of course, be so long as to interfere with the opening and 35 closing of the ventilator, consequently said buffer will not extend the full width of the associated shade in the event said shade be wider than the sash.

The primary object of my invention is to 40 provide a swinging ventilator, in a window sash, with means to prevent a shade supported inside of such sash from becoming abraded, cut, or worn by contact with said ventilator when the latter is open, such contact, 45 in fact, being prevented, and this without interfering with the operation of rolling said shade up or down, on the one hand, or interfering with the action of the ventilator, on the other hand. In the absence of a device 50 of this character the shade elements, when the shade is in lowered position, become abraded and even cut through by the inner top edge of the swinging ventilator, when said ventilator is open, so that in a short 55 time the shade becomes seriously impaired and may be so injured as to render the same

unfit for further use. The friction between this device and the shade, owing to the construction of said device, is so slight and of such a nature as to be negligible.

A further object is to provide a device of this character which is very simple and inexpensive in construction, and may readily be applied to any ventilator, so that said device is capable of large use or of a wide 60 application.

Another object is to afford anti-friction means for thrusting inwardly a shade which is suspended close to the window, when the ventilator is opened.

Other objects and advantages will appear in the course of the following description.

I attain the objects and secure the advantages of my invention by the means illustrated in the accompanying drawings, in 75 which—

Figure 1 is an inside elevation of a window and shade, showing the latter unrolled or lowered in front of the window sash, in which there is a ventilating section equipped 80 with a buffer that forms the essential element of the present invention, and which ventilator is in open position, portions of said shade being broken away to disclose more fully the parts and members that otherwise would be hidden thereby; Fig. 2, 85 an end elevation of the elements illustrated in the first view, and Fig. 3, an end elevation of a slightly different arrangement of the shade, the latter in this case being suspended 90 from the sash, instead of from brackets as in the first case.

Similar reference characters designate similar parts throughout the several views.

In the following description the terms 95 front and rear, and inside and outside, or equivalent expressions, as applied to the elements in the drawings, respectively indicate the side of such elements that is toward the center of the room in which they are located, and the side of such elements that is next to the adjacent wall of said room and the window or sash set therein.

In the drawings, a shade is represented at 1, and the same is shown unrolled or let 105 down to exclude the sun's rays which pass through the window in connection with which the shade is employed. A roll-up cord for the shade 1 and fixtures for said cord are respectively represented at 2 and 110 3—3, in Fig. 1, the same being omitted from Figs. 2 and 3. There is also represented a

steel or other metallic sash 4 of a window, which sash is provided in the center with a ventilating section or ventilator 5. The ventilator 5 at each end is pivotally connected, 5 at 6, with an adjacent rail of the sash. The axial line of the pivots, by means of which the ventilator 5 is connected with the window sash or with two of the rails thereof, is near the horizontal center of said ventilator, so that the latter can be tilted inwardly at the top and outwardly at the bottom for the admission of air.

10 Sashes having pivotally-connected ventilator sections, such as I have described 15 above, are commonly used in the construction of concrete and brick buildings wherein no wood is employed.

The shade 1 is provided with the usual reinforcing moulding strips 7 at the top and 20 bottom, and such shade may be attached at the top directly to the support therefor by means of the top moulding, but in the first two views such moulding is attached to an auxiliary strip 8, which strip is secured to 25 the front ends of a pair of forwardly-extending brackets 9, and in Fig. 3 to a strip 10. The brackets 9 are secured at their rear ends to the upper part or top of the sash 4, adjacent to the sides thereof, and the strip 10 30 is also attached to the upper part or top of the sash. These are but two of quite a number of different means by which the shade 1 can be supported or suspended at the top, and the present invention is not affected materially or limited by or to any 35 particular means of suspension for the shade.

In the first construction or arrangement 40 the brackets 9 project into the room beyond the opening in the wall in which the window sash 4 is set, consequently the shade 1 may, if desired, be wider than said sash; while in the example shown in Fig. 3 the top of the shade is supported within the aforesaid 45 opening, and said shade must, therefore, be limited in width to the width of the opening.

The cord 2 is manipulated in the customary manner for rolling the shade and permitting the same to unroll.

50 Across the top of the ventilator 5 in each case is a buffer 11, which buffer on the side toward the interior of the room has a convex surface. In the present instance each buffer 11 consists of a sheet-metal member 55 having an oval or partly round shape in cross section, and of a flange 12 which is riveted or otherwise securely attached to the inner face or side of the ventilator 5, at or adjacent to the top thereof. The buffer 11 60 may be no longer than the width of the ventilator 5 to which it is attached, but preferably said buffer will be as long as the width of the sash 4, in order that said buffer shall 65 present a greater amount of surface for contact with the shade 1, or have a longer range

of contact, so that there will be no liability on the part of said shade of becoming distorted by reason of its contactual relationship with the buffer, as might sometimes occur if the buffer were shorter.

70 When the shade 1 is let down in front of the ventilator 5, in the first construction or arrangement, it is supported by the brackets 9 a sufficient distance from the sash 1 to enable the ventilator 5 to be opened to the required extent without interfering in any way with said shade. Now, when the shade 1 is blown rearwardly or toward the sash 4, by currents of outgoing air, it encounters or is restrained by the contiguous buffer 11, 75 which projects beyond the upper inner edge of said ventilator, both in this and the other example, and said shade is thus prevented from encountering said edge, as it would do in the absence of said buffer, and from 80 being abraded, cut, or otherwise injured by said edge. The portion of the buffer 11 which contacts with the shade 1, or with which the shade comes into contact being convex, reduces the amount of friction between the parts and obviates almost entirely or reduces to the minimum the wear and tear of the shade. The object of the buffer 11 is attained whenever the shade 1 is unrolled far enough to enable the same to come into 85 contact with said buffer. This is true, of course, in every case.

90 In the Fig. 3 construction or arrangement, when the shade is rolled up completely, and it is desired to unroll the same to a point below the horizontal plane of the top of the ventilator 5 when open, it is necessary to lower the shade before said section is tilted.

Then, when the ventilator 5 is tilted or 100 opened, the buffer 11 attached thereto is brought into contact with the shade and thrusts the latter forwardly into the room, ahead of the top of the ventilator and a sufficient distance to permit said ventilator to be opened to the extent desired, and the 105 shade is held in this position as long as the ventilator remains open.

In this example, the buffer 11 serves the double purpose of thrusting the shade inwardly or forwardly to permit the ventilator to be properly operated, and of affording a medium for reducing the friction between the contacting members so as to avoid abrading or cutting the warp of the shade, or otherwise injuring the shade, as would occur if the latter were 110 to come into direct contact with the top of the ventilator itself when open or partly open. Thus it is seen that the buffer 11 here serves the same purpose as in the first case, and in addition thrusts the shade 1 into the 115 room beyond the vertical plane of the shade support, which plane is inside of the opening in the wall for the sash 4.

120 In Fig. 3 the shade 1 can be rolled up even when the ventilator 5 is fully open 125

so that the top thereof projects a considerable distance into the room.

It is now clearly apparent that the buffer 11 affords simple, inexpensive, practicable, 5 and efficient means for protecting a shade from a ventilator when open, and enabling said ventilator to be opened without injuring the shade when the latter is supported close to the sash.

10 As already set out at some length, the supporting means for the shade may be varied to a large extent structurally and in regard to location, and in addition it should be stated that more or less change in the shape, 15 size, construction, and arrangement of the buffer may be made, and all without departing from the spirit of my invention or exceeding the scope of what is claimed.

What I claim as my invention, and desire 20 to secure by Letters Patent, is—

1. In a horizontally-arranged shade appliance, of the class described, a window-sash-ventilating section, a shade adapted to be let down inside of said section, the latter 25 being movable toward the former when let down, and anti-friction means intervening between said section when open and said shade when let down.

2. In a horizontally-arranged shade appliance, of the class described, a window-sash-ventilating section, a shade adapted to be let down inside of said section, the latter being movable toward the former when let down, and anti-friction means carried by 35 said section in contacting relationship with said shade when let down and the section is moved toward the same.

3. In a horizontally-arranged shade appliance, of the class described, a window-sash-ventilating section, a shade adapted to be let down inside of said section, the latter being movable toward the former when let down, and anti-friction means carried by 40 said section to prevent contact between the same and said shade when let down and the section is moved toward the shade.

4. In a horizontally-arranged shade appliance, of the class described, a window-sash-ventilating section, a shade adapted to be let down inside of said section, the latter being movable toward the former when let down, and anti-friction means carried by 45 said section to thrust inwardly said shade when let down, and the section is moved toward the same.

5. In a horizontally-arranged shade ap-

pliance, of the class described, a window-sash-ventilating section, a shade adapted to be let down inside of said section, the latter being movable toward the former when let 60 down, and anti-friction means carried by said section to thrust inwardly said shade when let down and the section is moved toward the same, and to prevent the shade from coming into contact with said section. 65

6. In a shade appliance, of the class described, a horizontally-hung, inwardly-swinging window-sash-ventilating section, a shade adapted to be let down inside of said section, and a horizontal buffer carried by 70 that portion of said section which opens into the room and toward the shade when let down, to prevent contact between said section and said shade.

7. In a horizontally-arranged shade appliance, of the class described, a window-sash-ventilating section, a shade adapted to be let down inside of said section, the latter being movable toward the former when let down, and a buffer having a flange for attachment to said section, said buffer being interposed between said section and said shade when let down and the section is moved toward the same. 75

8. In a horizontally-arranged shade appliance, of the class described, a window-sash-ventilating section, a shade adapted to let down inside of said section, the latter being movable toward the former when let down, and a horizontal buffer carried by that 80 portion of said section which opens into the room and toward the shade when let down, to prevent contact between said section and said shade, said buffer extending beyond the ends of said section. 85

9. In a horizontally-arranged shade appliance of the class described, a window-sash-ventilating section, a shade adapted to be let down inside of such section, the latter being movable toward the former when let 90 down, and a horizontal buffer carried by that portion of said section which opens into the room and toward the shade when let down, to prevent contact between said section and said shade, said buffer consisting of a rolled-up member having a part for attachment to the section. 95
